[57] CLAIM

The ornamental design for a combination nightlight and electrical outlet cover, as shown and described.

DESCRIPTION

FIG. 1 is a top, front perspective view of a combination nightlight and electric outlet cover showing our new design, the outlet wall plate being shown in broken lines for illustrative purposes only;

FIG. 2 is an exploded bottom, rear perspective view thereof;

FIG. 3 is a top plan view thereof;

FIG. 4 is a side elevational view thereof, the opposite side being a mirror image;

FIG. 5 is a bottom plan view thereof.

FIG. 1

FIG. 3

FIG. 4

FIG. 5
